UNITED STATES PATENT OFFICE.

FRANK KINZBACH, OF HOUSTON, TEXAS.

WHIPSTOCK.

Application filed June 10, 1926. Serial No. 115,016.

This invention relates to new and useful improvements in a whip stock.

One object of the invention is to provide a whip stock of the character described 5 equipped with a locking device whereby the whip stock may be secured in fixed position in a casing, or pipe, to be perforated.

In drilling wells it often happens that the lower end of the bore becomes obstructed, by 10 the dropping of a bit, or other object therein so that the drilling cannot proceed in the original bore, and in such case the casing in the well bore must be perforated on one side, above said obstruction, and the bottom of 15 the original hole side tracked by the continuing of the drilling operations through said lateral perforation in the casing. In order to perforate the casing a whip stock is lowered into the bore, the upper end of 20 the whip stock being wedge shaped so as to form a deflecting guide and a drilling tool is then let down into the casing between the inclined face of the whip stock and the opposing side of the casing and is rotated until 25 the casing is cut through and the original bore side tracked at its lower end. Unless the whip stock is anchored in the casing the rotation of the drilling tool often causes the whip stock to turn, or rotate about a 30 vertical axis thus interfering with the work of perforating the casing and making it difficult or impossible to perforate the same. It is an object of this invention to provide a means for securely locking the whip stock 35 against rotation in the casing during the milling operation.

With the above and other objects in view this invention has particular relation to certain novel features of construction, operation and arrangement of parts an example 40 of which is given in this specification and illustrated in the accompanying drawings, wherein:—

Figure 1 shows a vertical sectional view 45 of the well casing showing a fragmentary sectional view of the whip stock and also showing a drilling tool associated therewith.

Figure 2 shows a fragmentary side view, partly in section of the whip stock, as located in the casing.

Figure 3 shows a fragmentary elevational view of the whip stock in the casing, and

Figure 4 shows a horizontal sectional view taken on the line 4—4 of Figure 3.

Referring now more particularly to the drawings, wherein like numerals of refer-

ence designate similar parts in each of the figures, the numeral 1 designates a well casing to be perforated, and the numeral 2 designates a liner located in and extending beneath the lower end of the casing. The numeral 3 designates a whip stock proper whose lower end is substantially cylindrical and which tapers to a point at the upper end thus forming an inclined face 4 against which the milling tool 5 works. The lower end of the whip stock has a slot 6 therein in which the hinge member 7 is pivoted and this hinge member has a depending outwardly threaded neck 8 on which the upper 60 end of the tubular sleeve 9 is threaded. A downwardly tapering anchor 10 is adapted to seat in the upper end of the liner 2 and this anchor has an upwardly extending shank 11, which telescopes up into the sleeve 70 75 9. In the sleeve 9 the shank 11 has a transverse notch 12 formed with a downwardly and outwardly sloping bearing face 13 and provided with an external shoulder 14 at its upper end. There is a jaw 15 which fits 80 through the slot 16 in the sleeve 9, whose inner end is beveled to conform to the slope of the face 13, and whose outer end is formed with a sharp edge adapted to bite into the casing 1 and said sleeve is held against detachment by the pin 17 which works through the oblong slots 18, in said jaw.

When it is desired to use the whip stock it is lowered into the casing and the anchor 10 seated in the upper end of the liner 2, 90 and thereupon the sleeve 9 moves on down relative to the shank 11 carrying the jaw 15 downwardly with it and the sloping face 13 will force said jaw outwardly against the casing and this will anchor the whip stock 95 against rotation in the casing 1 during the drilling operation.

What I claim is:—

1. A whip stock comprising an elongated body having a taper extending throughout a major portion thereof to provide a wedging face, a hinged member pivoted to the lower end of said body, a tubular sleeve depending from said hinge member, an anchor having a shank which telescopes into said sleeve member, said shank having a downwardly and outwardly sloping bearing face with a shoulder at the upper end of said face, said sleeve having a slot and a jaw working through said slot and whose inner end bears against said face. 100 105 110
2. A whip stock comprising an elongated

22

body having a taper extending throughout the major portion thereof to provide a wedging face, a hinged member pivoted to the lower end of said body, a tubular sleeve depending from said hinge member, an anchor having a shank which telescopes into said sleeve member, said shank having a downwardly and outwardly sloping face with a shoulder at the upper end of said face, said sleeve having a slot and a jaw working through said slot whose inner end bears against said face and whose outer end is formed with a sharp edge.

3. A whip stock comprising an elongated body having a taper which extends throughout a major portion thereof to provide a wedging face, a member hingedly connected to the lower end of said body, an anchor, telescoping parts connected to said hinge member and said anchor respectively, one

of said telescoping members having an outwardly sloping face and the other telescoping member having a slot opposite said face and a jaw working through said slot whose inner end bears against the face.

25

4. A whip stock comprising an elongated body having a taper which extends throughout a major portion thereof to provide a wedging face, an anchor, relatively slidible parts, one hingedly connected to said body and the other connected to said anchor, one of said slidible parts having a sloping bearing face, and the other of said parts having a bearing, and a jaw working through said bearing, whose inner end bears against said sloping face.

30

In testimony whereof I have signed my name to this specification.

FRANK KINZBACH.
